ATTORNEY

UNITED STATES PATENT OFFICE.

ROBERT SNEIDER, OF BROOKLYN, NEW YORK.

DESIGN FOR AN INKSTAND.

SPECIFICATION forming part of Design No. 16,847, dated August 10, 1886.

Application filed July 8, 1886. Serial No. 207,517. Term of patent 7 years.

To all whom it may concern:

Be it known that I, ROBERT SNEIDER, a citizen of the United States, and a resident of Brooklyn, in the county of Kings and State of New York, have invented and produced a new and original Design for an Inkstand, of which the following is a specification, reference being had to the accompanying drawing, forming part thereof.

10 The drawing represents a perspective view of my newly-designed inkstand.

This invention relates to a new design for an inkstand. It consists of a rectangular scalloped base, *a*, and feet *b*, representing horses' feet. *c* are horseshoes projecting upward and inward from the four corners of base *a*. *d* is a ring, and *e* a cover which simulates a jockey-cap. From the two front corners of the stand

there extend forward two projections, *f*, as shown.

20 The characteristic feature of the design consists of an inkstand having the parts representing the cap, feet, and horseshoes, all as shown and described.

I claim—

1. The design for an inkstand having the parts representing base *a*, feet *b*, horseshoes *c*, ring *d*, and cap *e*, substantially as shown.
2. The design for an inkstand having the parts representing base *a*, feet *b*, horseshoes *c*, ring *d*, cap *e*, and projections *f*, substantially as shown.

25 ROBERT SNEIDER.
